UNITED STATES PATENT OFFICE.

FRANK J. BORER, OF ROSELLE PARK, NEW JERSEY.

PRESSURE-RETAINING VALVE FOR FLUID BRAKES.

Application filed August 4, 1921. Serial No. 489,734.

To all whom it may concern:

Be it known that I, FRANK J. BORER, a citizen of the United States, residing at Roselle Park, in the county of Union and 5 State of New Jersey, have invented certain new and useful Improvements in Pressure-Retaining Valves for Fluid Brakes, of which the following is a specification.

My invention relates to an apparatus 10 forming a part of a railway equipment and refers more particularly to an essential part of the automatic air or fluid brake now in general use on passenger cars, freight cars, and locomotives. This apparatus is generally known as a pressure retaining valve, 15 and its function is to provide suitable means for controlling the exhaust of air or pressure fluid from a triple valve exhaust port to the atmosphere.

One object of my invention is to make the 20 control of air from the exhaust port more positive and reliable and to increase the factor of safety in handling the train on grades while the trains are being controlled by the 25 engine-man by means of the air or fluid brake.

A further object of my invention is to retain all good features now present in existing retaining valves, but in addition it embodies 30 certain desirable new features which have not been employed heretofore.

In order to fully comprehend the value of this invention, it should be mentioned that 35 vent ports of all present standard types of pressure retaining valves are unprotected against ice, snow, fine sand, dust, grease, or oil, and are in such position that they may easily be plugged up by means of a piece of wood or wire or the like.

This practice of plugging up vent ports is often resorted to by trainmen on nearly 40 every railroad when running down grade. The pressure retaining valves are not always given needed attention and for that 45 reason a considerable number of defective valves are found to be in use. Trainmen whose duty it is to operate valves and turn the handles for increasing the pressure in the valve at the summit of a grade will, contrary to their instructions, plug vent ports 50 in order "to make them hold." But the men even go further than that in order to check the speed of a train. They will remove the retainer vent cap or weight cap and insert 55 all sorts of foreign matter, such as leather,

old rubber gaskets, cotton waste, valve packing, etc. underneath or on top of the retaining valve weight, thereby destroying its automatic relief feature. This often takes place when the cars are being painted and 60 sand blasted at the shops. On the spring type of pressure retaining valves, the trainmen often remove the vent cap, and increase the tension of the spring four or five fold by stretching it and then putting it back in 65 place again under the cap. This practice is carried out not only on the defective valves, which would be inexcusable, but also on brand new valves.

Now, in order to make such practice impossible another object of my invention is to provide a positive remedy therefor by changing the construction of the valve, that is to make it impossible for train-men to take apart and to plug up the retaining 70 valves. For this reason I place the valve body with all the mechanism and delicate parts in a closed housing or bracket and secure this bracket in its place on the car or locomotive. I furthermore provide an automatic vent port leading to the atmosphere 75 which is so concealed and protected that no foreign material can possibly enter into it either by accident or purposely. As train-men are not provided with any tools whatever, of the kind necessary to remove retaining valves bodily from cars, there is no way for them to tamper with a valve which must be removed bodily for repair or re-setting. 80

Still another advantage of constructing the valve in this manner and attaching the housing or bracket and valve both to the car is that there is no likelihood of breakage of any metal parts with the exception of the 85 projecting ears for securing the valve in position which are now on the housing and if broken may be easily repaired by electric or acetylene welding. For this reason scrapping of parts will not occur as often as with 90 the existing kind of valves which makes considerable saving in repair and upkeep. As none of the interior parts can be removed without adequate tools it will be necessary to remove the entire valve including the housing whenever repairing or cleaning is necessary which every time would be done at the 95 work-shop or air brake cleaning or testing stations.

In order to give an idea of the injurious 100

consequences of plugging the valve it might be mentioned that approximately 25,000,000 chilled cast iron wheels are used on railroads in the United States. When the 5 wheels are subjected to severe strain, overheating, or sliding caused by too hard braking, depending on plugged retaining valves, a great number thereof have to be scrapped annually due to brake-burn, slid-flat surfaces, heat cracks and similar defects, it will 10 be evident that all possible precautions should be taken for preventing such plugging of valves. Many accidents have been caused through burst or cracked wheels from 15 the same cause.

In accordance with opinion of practical air brake mechanics, experts and engineers, the ratio of the effective retarding force or 20 brake force should be in proportion to the weight of each car and train. For this reason it is necessary to use valves that may be regulated to retain pressure of at least two different magnitudes so that a low pressure may be retained in the brake cylinder 25 on the empty car, or when descending a grade of less than 1% with a train composed of loaded cars, while a high pressure may be retained while descending steep grades with a train of loaded cars.

30 My retaining valve is designed to obtain as nearly as possible the same ratio on loaded and unloaded cars, and for this reason, for low pressure the valve is preferably regulated to ten pounds per square 35 inch in the brake cylinder and to thirty pounds for high pressure.

Other features and advantages of my invention will be evident from the description and the illustration thereof.

40 In the accompanying drawings:

Figure 1 is a vertical, sectional view along line 1—1 of Figure 2;

Figure 2 is a vertical sectional view along the line 2—2 of Figure 1 illustrating one 45 embodiment of the invention;

Figure 3 is a fragmental view of a valve in position for retaining a high pressure in the brake cylinder;

Figure 4 is a similar view of Figure 3 50 showing the position of a valve giving a low pressure in the brake cylinder;

Figure 5 is a bottom plan view of the valve housing;

Figure 6 is a fragmental elevation of the 55 guard for the air vent;

Figure 7 is a transverse section of the housing taken along line 7—7 of Figure 1.

The reference number 10 denotes a housing 60 for the valve containing an outer chamber 11 of cylindrical shape open at the bottom and closed at the top, and a projecting lug 13 preferably flat sided for providing a good grip for a wrench. Below the lower edge of the cylindrical part of the housing 65 is provided a transverse flat bar 14 the ends

of which form lugs for securing bolts for which the holes 15 are provided. The lower part of the cylinder is threaded for receiving the valve body 16 and three narrow borings 17 are shown as vent holes constituting communication between the outer chamber and the atmosphere. 70

The body 16 is of irregular shape but its upper end is provided with threads 18 corresponding to those on the lower end of the 75 housing 10, so that the valve body 16 may be screwed into the housing and form a tight joint therewith. The lower end of the valve body 16 is neck shaped and provided with threads 19 to receive the fluid pressure pipe 20, and the exterior of the neck portion is preferably flattened to accommodate a wrench. An inlet passage 21 leads from the pipe 20 to the valve seat 22 running transversely to the vertical axis of the 80 valve body and this seat is preferably provided with a soft metal bushing 23 which is cone shaped and fits around the valve cone 24 having at its small end a handle 25 attached to it for turning the cone. A cap 90 26 threaded into the valve body closes up the large end of the valve seat and has a counter-bore 27 to receive a spring 28 which exerts a pressure against the large end of the cone in order to obtain a tight fit in its 95 seat. Midway between the two ends of the cone a passage 29 has been bored and this passage is adapted to form communication between passage 21 and one or two of the ports 30, 31, and 32, of which 30 stands in 100 communication with the atmosphere through exhaust pipe 33, and port 31 leads up to the high pressure valve 34 and port 32 leads to the low pressure valve 35. When it is desired to test the brake cylinder and its 105 connections for leakage, an air pressure gage takes the place of the exhaust pipe 33. As will be seen in Figure 1 when the handle 25 hangs straight down, the passage 21 is connected with the port 30 through passage 110 29. When the handle 25 is turned about 45° up the passage 29 connects passage 21 with port 31 (see Figure 3) leading to the high pressure valve and when finally the handle is turned into horizontal position 115 as shown in Figure 4, the passage 21 communicates with the low pressure valve 35 through port 32. By means of a flaring out of lower portion of port 31 leading to the high pressure valve and providing a 120 similar flare 36 on the upper end of passage 29, it can be seen in Figure 4 that communication is also open through port 31 as well as through port 32.

Suitable bushings 37 are inserted in the 125 upper portions of the ports 31 and 32 forming seats for valves 34 and 35 which are of the ordinary poppet kind. These two valves 34 and 35 support on their heads a bridge or lever 40 which has a counter-bore for each 130

of the heads of slightly larger diameter than the latter. As Figures 2 and 5 clearly show these valves and the corresponding counter-bores are placed at different radial distances 5 from the vertical axis of the valve body so that the pressure from the spring 41 exerted centrally against the bridge will have different effect on the two valves. The spring 41 is mounted around the central knob 42 on top 10 of the bridge 40 and is guided with its upper end by a pin 43 secured in a plug 44 which is threaded in the neck of a valve cap 45. This cap forms the inner chamber 46 of the retaining valve and is threaded to be screwed 15 on the neck 48 at the top of the valve body.

The valve body is provided with a recess 47 in which the bridge 40 fits loosely at both ends in order to give sufficient play between the bridge and the edge of the valve body 20 when pressure is applied on either one of the valves 34 or 35. When fluid pressure passes up through port 31 and lifts the high pressure valve 34, this valve pressing against one end of the bridge will raise the same 25 against the spring pressure and with the other valve 35 as fulcrum, and the opposite takes place when fluid pressure is permitted to pass by valve 35. It will readily be seen that the spring 41, by means of this arrangement, 30 will exert less resistance against the valve 35 than against valve 34. And a stronger spring can now be used which is easier to manufacture and adjust than if individual springs were used for each valve 35 and the relative distances from the axis of the valve body, with which the spring is co-axial, to the axes of the individual valves 34 and 35, has been so selected that the spring will cause a resistance equivalent to 40 ten pounds per square inch on valve 35 and thirty pounds per square inch on valve 34. This pressure may, of course, be varied in accordance with requirements and circumstances.

45 In the neck portion of the inner chamber cap 45 a narrow vent 50 connects the inner chamber 46 with the outer chamber 11 so that there is no direct communication from the inner chamber to the atmosphere but 50 such communication must take place through the small vent 50 in the outer chamber 11 and then through vent holes 17 provided in the housing. As these latter vents 17 may be stopped up by snow, ice, or any other obstructions an additional to safety vent 51 is provided in the valve body 16 as best seen in Figures 2 and 6. This runs perpendicularly near the edge of the valve body and terminates at its lower end in a pocket 52. This 60 pocket is formed by a depending nose 53 and a surrounding lip 54 which nose and lip form an outlet for the vent 51. In order to still further protect this vent from accidental or intentional closing it has been 65 placed on the back part of the valve body

so that when the valve is assembled and installed in position, the vent 51 will be located opposite the bar 14 between the bolts securing the housing to the wall of a car and is therefore found to be very inaccessible.

70 The operation of a retaining valve is as follows:

When a train is running on level ground and no brakes applied the valve handle 25 stands in position I as shown in Figure 2 75 when the pressure fluid passes from passage 21 through passage 29 chamber 30 and out through exhaust pipe 33.

Upon descending a grade, the valve handle 25 should be turned to position II as shown 80 in Figures 2 and 3 for loaded or heavy cars, when the fluid pressure passes from passage 21 through passage 29 port 31 past valve 34 into the inner valve chamber 46 thus the retaining pressure is about thirty pounds. For 85 empty or light unloaded cars the handle 25 has to be turned to position III as seen in Figures 2 and 4 which will permit the fluid pressure to pass from pipe 20 through passage 29, chamber 32, past valve 35 and the 90 chamber 46, maintaining a lower pressure of about ten pounds per square inch in the brake cylinder. In case the pressure on pipe 20 should exceed the resistance exerted by spring 41 on valve 35, valve 34 would also 95 open and remain so until the pressure has been evened out.

As long as the pressure in the brake cylinder and pipe 20 is in excess of the resistance exerted by spring 41 on valves 35 and 34, 100 these two valves will open and allow the pressure fluid to escape into chamber 46. However, port 50 is purposely restricted to cause a blow down of brake cylinder pressure in accordance with pre-determined 105 standards of time in seconds. Therefore, pressure fluid will enter chamber 46 much faster than port 50 can relieve same. This temporary accumulation of pressure in chamber 46 will cause temporary closing of 110 valves 34 and 35 with the assistance of spring 41. This process of temporary opening and closing of valves 34 and 35 will continue until the pressure remaining in the brake cylinder and the exhaust pipe is 115 slightly less than the pressure exerted by spring 41 upon the bridge 40 and valves 34 and 35.

Having thus described the invention what is claimed as new is:

1. In a valve having one inlet and two outlet ports, a valve for each port, a bridge member fulcrumed on each of said outlet valves, and common means for operating the said bridge for exerting a different resistance against each outlet valve.
2. In a valve having one inlet and two outlet ports, a valve for each port, a bridge member fulcrumed on each of said outlet valves and a spring pressing against said 130

bridge to close the outlet ports, said spring contacting with the bridge nearer one of said outlet valves than the other.

3. A valve provided with an inner and an outer chamber, a port connecting said chambers and a guarded port leading to the atmosphere from said outer chamber.

4. A valve provided with a high and a low pressure chamber, a port connecting said chambers, and a guarded port leading to the atmosphere from said low pressure chamber.

5. A valve provided with a high and a low pressure chamber, a port connecting said chambers and a guarded port leading to the atmosphere from said low pressure chamber, said guarded port consisting of a concealed pocket with a narrow outlet to the atmosphere, and a passage connecting said pocket with the low pressure chamber.

20 6. A valve comprising a housing and a valve body, intercommunicating outer and inner chambers being formed between said housing and said valve body, said valve body being provided with a circuitous exhaust port communicating with said outer chamber.

7. A valve comprising a housing and a valve body, intercommunicating outer and inner chambers being formed between said housing and said valve body, said valve body being provided with a circuitous exhaust port communicating with said outer chamber, said port being situated behind the wall of said housing.

35 8. A valve comprising a housing and a valve body, intercommunicating outer and inner chambers being formed between said housing and said valve body, said valve body being provided with an exhaust port communicating with said outer chamber, a tongue covering said exhaust port and a lip across the outlet of said port.

9. In a fluid pressure retaining valve, a valve body having a pressure fluid inlet and a plurality of ports, one of which leads into the atmosphere, and a chamber member in which said other ports open, a valve member adapted selectively to connect with either one of said ports, said other ports being provided with outlet valves and means exerting different resistance against said outlet valves, said valve body having a vent communicating between said chamber and the atmosphere, said vent being provided 55 with a guard.

10. In a fluid pressure retaining valve comprising a housing and a valve body rigidly connected together and forming an outer chamber between them, said housing 60 having a projecting wall provided with lugs for securing the valve in position, and a plurality of vents leading from said cham-

ber to the atmosphere, a safety port provided in said valve body communicating with said outer chamber, its outlet being 65 situated opposite said projecting wall on the housing.

11. In a fluid pressure retaining valve comprising a housing and a valve body rigidly connected together and forming an outer chamber between them, said housing having a projecting wall provided with lugs for securing the valve in position, and a plurality of vents leading from said chamber to the atmosphere, a safety port provided in 70 said valve body communicating with said outer chamber, its outlet being situated opposite said projecting wall on the housing, a cap attached to said valve body within said outer chamber and forming an inner 75 chamber, communication being provided between said inner and outer chambers, a fluid pressure inlet in said valve body and a valve member provided with a passage diametrically across the same, a seat being provided in said valve body for said valve member and a plurality of ports leading from said valve seat to said inner chamber, a valve 80 plunger for each port and means exerting different resistance against each of said 85 valve plungers, said valve member being adapted to selectively connect one of said ports with said fluid pressure inlet.

12. In a fluid pressure retaining valve comprising a housing and a valve body rigidly connected together and forming an outer chamber between them, said housing having a projecting wall provided with lugs for securing the valve in position, and a plurality of vents leading from said chamber to the atmosphere, a safety port provided in 90 said valve body communicating with said outer chamber, its outlet being situated opposite said projecting wall on the housing, a cap attached to said valve body within 95 said outer chamber and forming an inner chamber, communication being provided between said inner and outer chambers, a fluid pressure inlet in said valve body and a valve member provided with a passage diametrically across the same, a plurality of ports leading from said valve seat, one of said 100 ports communicating with the atmosphere and two of said ports communicating with said inner chamber, a valve plug for each of said two ports, a bridge fulcrumed on each of said valve plugs, a spring within said inner chamber exerting pressure centrally against said bridge, each of said valve plugs being situated at a different distance from 105 said bridge center.

In testimony whereof I affix my signature.

FRANK J. BORER. [L. S.]
